CONCENTRATION AND USE OF METHYLCYCLOPENTANE IN 2,2,4-TRIMETHYLPENTANE ISOMERIZATION

Francis E. Condon, Bartlesville, Okla., assignor to Phillips Petroleum Company, a corporation of Delaware

Application June 30, 1949, Serial No. 102,394

3 Claims. (Cl. 260—683.5)

1

This invention relates to the isomerization of 2,2,4-trimethylpentane, sometimes called "iso-octane," and the use of methylcyclopentane therein as an inhibitor of side reactions. In one of its specific aspects the invention pertains to the isolation, by chemical means, of methylcyclopentane from admixture with cyclohexane and/or normal hexane, and use of the so-isolated material as an inhibitor in the aluminum bromide-catalyzed isomerization of 2,2,4-trimethylpentane to form 2,3,4-trimethylpentane, 2,3,3-trimethylpentane, and 2,2,3-trimethylpentane.

In the preferred embodiments the invention relates to an integrated process wherein an isoparaffinic by-product of the isomerization is employed as reactant in the methylcyclopentane isolation step. Other preferred aspects of the invention involve the use of the methylcyclopentane isolation steps to segregate and remove cyclohexane formed in the isomerization step by a side reaction involving isomerization of the methylcyclopentane inhibitor used therein.

This application is a continuation-in-part of my copending application Serial No. 701,848, filed October 7, 1946, now U. S. Patent No. 2,474,827.

The isomerization of 2,2,4-trimethylpentane ("iso-octane") is of interest in increasing the value of this material as motor fuel, for the research octane numbers of the isomers mainly produced, namely, 2,3,4-trimethylpentane, 2,3,3-trimethylpentane, and 2,2,3-trimethylpentane, are 0.22, 0.61, and 1.18 ml. tetraethyllead in "iso-octane," respectively. Furthermore, the trimethylpentanes other than 2,2,4-trimethylpentane are applicable as starting materials for chemical syntheses for which 2,2,4-trimethylpentane would be unsuitable. For example, 2,3,3-trimethylpentane and 2,2,3-trimethylpentane can be catalytically hydrogenolyzed to triptane (2,3,3-trimethylbutane) and methane, whereas 2,2,4-trimethylpentane would not yield triptane on hydrogenolysis (Ind. Eng. Chem., 39, 853 (1947).)

The isomerization of 2,2,4-trimethylpentane with aluminum bromide at 26° C., for example, results in an approximately 26 weight per cent ultimate yield of isomers, of which about 85 per cent are the trimethylpentanes other than 2,2,4-trimethylpentane. If the isomerization is conducted in the presence of methylcyclopentane, however, the ultimate yield of isomers is increased to as much as 65 per cent or more of the 2,2,4-trimethylpentane converted.

Methylcyclopentane, however, is ordinarily obtained in admixture with normal hexane and cyclohexane. Both of these hydrocarbons are

ineffective in increasing the yield of isomers from the 2,2,4-trimethylpentane and undergo practically no change during the isomerization of the 2,2,4-trimethylpentane. Thus, if such a commonly obtained mixture of methylcyclopentane, normal hexane and cyclohexane were used in admixture with 2,2,4-trimethylpentane during isomerization of the latter in order to obtain the beneficial effects of the methylcyclopentane on the yield of isomers from the 2,2,4-trimethylpentane, the inert cyclohexane and normal hexane would accumulate in recycle streams containing valuable methylcyclopentane, which would eventually have to be withdrawn and discarded, at least in part. Furthermore, the presence of the inert, cyclohexane and normal hexane, would necessitate the use of enlarged equipment for the treatment of a given amount of 2,2,4-trimethylpentane in a given time. Consequently, it is advantageous to concentrate the methylcyclopentane from its admixture with cyclohexane and normal hexane in order to use it most effectively as an inhibitor of side reactions during the isomerization of 2,2,4-trimethylpentane.

Methylcyclopentane (B. P. 71.8° C.) can be separated from normal hexane (B. P. 68.7° C.) and from cyclohexane (B. P. 80.7° C.) by fractional distillation. But the closeness of the boiling points of these three hydrocarbons requires that the fractionating equipment be rather complex and exceedingly efficient. Methylcyclopentane can be separated from cyclohexane and normal hexane, however, by a chemical means requiring inelaborate fractionating equipment, as described in my copending application, now U. S. Patent No. 2,474,827. As disclosed therein, a mixture of methylcyclopentane with cyclohexane and/or normal hexane may be contacted with tertiary-butyl chloride, or other tertiary or less preferably secondary alkyl or cycloalkyl halide, in the presence of aluminum chloride or bromide so as to effect as the principal reaction a halogen-hydrogen exchange whereby the methylcyclopentane is converted to a tertiary halide, 1-chloro-1-methylcyclopentane, and the tertiary-butyl chloride is converted to isobutane:

The cyclohexane and normal hexane are unchanged. The 1-chloro-1-methylcyclopentane (B. P. about 122° C.) is easily separable by fractional distillation from the other components in

the mixture. It is then contacted in a second stage with isobutane or isopentane in the presence of aluminum chloride or bromide so as to effect as the principal reaction a halogen-hydrogen exchange whereby the 1-chloro-1-methylcyclopentane is reconverted to methylcyclopentane and the isobutane is converted to t-butyl chloride.

At least part of the isobutane used as reactant in this stage may be that formed in the first stage above. But in accordance with a preferred embodiment of the present invention, a part of this isobutane, that used to replace losses engendered by the inefficiency of the chemical reaction for example, is obtained as a by-product of the 2,2,4-trimethylpentane isomerization stage as disclosed further herein.

Methylcyclopentane, then, is obtained by fractional distillation from the product of the second halogen-hydrogen exchange step just described and in accordance with the copending application, now U. S. Patent No. 2,474,827. In the practice of the present invention, this methylcyclopentane, freed from cyclohexane and normal hexane, is admixed with 2,2,4-trimethylpentane and the mixture is contacted with an aluminum halide isomerization catalyst in order to isomerize a part of the 2,2,4-trimethylpentane. Now it is a characteristic of this isomerization reaction that isobutane is produced as a by-product in an amount corresponding to about 18-25 per cent of the 2,2,4-trimethylpentane converted. Furthermore, although methylcyclopentane inhibits the formation of most of the by-products formed during isomerization of the 2,2,4-trimethylpentane, it does not inhibit the formation of the isobutane. Therefore, isobutane is made available by the isomerization step and, according to the practice of the present invention, is utilized at least in part in the second halogen-hydrogen exchange step described above in which 1-chloro-1-methylcyclopentane is converted to methylcyclopentane.

During the isomerization of 2,2,4-trimethylpentane in the presence of methylcyclopentane, a part of the methylcyclopentane is isomerized to cyclohexane, which would tend to accumulate in recycle streams unless a part of it were continually removed. As an additional feature of this invention, therefore, a part of the methylcyclopentane recycle stream is diverted to the first halogen-hydrogen exchange stage, the cyclohexane is removed and discarded while the methylcyclopentane is recovered for reuse in the isomerization step.

From the foregoing it will be apparent that a principal object of this invention is to provide a process for the isomerization of 2,2,4-trimethylpentane wherein use of methylcyclopentane as an inhibitor of side reactions is facilitated by removal of cyclohexane and/or normal hexane found in admixture therewith in the primary source of the methylcyclopentane and/or formed by a concurrent isomerization of part of the methylcyclopentane being used as inhibitor.

Another object of the invention is to isolate methylcyclopentane from admixture with cyclohexane and/or normal hexane for use as an inhibitor of side reactions in the isomerization of 2,2,4-trimethylpentane, thereby increasing the yield of desired trimethylpentane isomers.

A further object is to get rid of cyclohexane formed in the methylcyclopentane-inhibited isomerization of 2,2,4-trimethylpentane.

Yet another object is to employ a halogen-hydrogen exchange reaction for separation of methylcyclopentane from cyclohexane found in admixture therewith both in a primary source of same and in a recycle stream in a 2,2,4-trimethylpentane isomerization process.

A still further object is to utilize light isoparaffinic material formed as by-product by the isomerization of 2,2,4-trimethylpentane as reactant for converting 1-chloro-1-methylcyclopentane into methylcyclopentane which is employed as inhibitor in said isomerization.

Further objects and advantages of my invention will be apparent, to one skilled in the art, from the foregoing and following disclosure and discussion.

The accompanying drawing shows schematically one arrangement of apparatus elements and flow of materials therethrough suitable for the practice of my invention in a preferred embodiment. It will be understood that the drawing is diagrammatic only, and that many suitable conventional forms of equipment may be employed as desired for any particular situation. Auxiliary elements of apparatus, such as pumps, valves, heat exchangers, agitators, coolers, condensers, separators, automatic control means, and the like, are not shown in the drawing for the sake of simplicity, inasmuch as the supplying of such elements is well within the skill of the art.

In the drawing a commonly available mixture of methylcyclopentane, cyclohexane and normal hexane, such as one derived by simple fractional distillation of natural gasoline, enters reactor 4 through inlet conduit 2. Tertiary butyl chloride enters reactor 4 through conduit 3. Suitable halogen-hydrogen exchange catalyst, such as a fluid aluminum chloride-hydrocarbon complex, enters reactor 4 through line 5. Reactor 4 may comprise any suitable equipment for effecting a rapid and intimate intermixture of reactants with catalyst, for example a mixing pump or agitated pressure vessel. The rate of flow of reaction mixture through reactor 4 is chosen to give the desired short reaction time. Contents of reactor 4 are withdrawn through line 6 into settler 7 in which a heavier catalyst phase separates from a lighter hydrocarbon phase. If necessary or desired, water or other materials for quenching the reaction may be introduced through conduit 38. The heavier catalyst phase is withdrawn from settler 7 through outlet line 8 and may be revived by means not shown, for example by addition of fresh solid aluminum chloride. Preferably at least part of the catalyst phase is recycled from settler 7 via lines 8, 9 and 5 to reactor 4. The catalyst-free lighter hydrocarbon phase is passed from settler 7 through conduit 10 to fractionation system 11 which ordinarily comprises a series of two or more fractional distillation columns and associated equipment. Prior to fractionation this phase may be treated by conventional means to remove dissolved and/or suspended catalyst.

From fractionator 11, the following fractions are withdrawn: (1) A low-boiling fraction, comprising chiefly isobutane, which is passed through line 12 to reactor 18. (2) A fraction, comprising unreacted tertiary-butyl chloride, which is recycled, as through lines 13, 15, 3 and 2 to reactor 4. (3) A fraction, comprising a cyclohexane-n-hexane concentrate containing some methylcyclopentane, which may be withdrawn as a prod-

uct of the process through outlet 14, but part of which is preferably recycled, as through conduits 14, 15, 3 and 2 to reactor 4 for further concentration. The concentrate recovered through line 14 may be passed to a separate isomerization stage (not shown in the drawing) in which a part of the cyclohexane is converted to methylcyclopentane and a part of the normal hexane is converted to isohexane, and from which a cyclohexane-n-hexane fraction, enriched in methylcyclopentane, is returned to reactor 4 through line 2. (4) A fraction, comprising 1-chloro-1-methylcyclopentane, which is passing through lines 16 and 12 to reactor 18. (5) A minor fraction, comprising heavy hydrocarbons formed by side reactions such as alkylation and/or polymerization, which is withdrawn through outlet 17.

The mixture of isobutane and 1-chloro-1-methylcyclopentane in line 12, supplemented from line 32 as needed with isobutane formed in reactor 35 in order to maintain preferably at least a 1:1 mol ratio of isobutane to 1-chloro-1-methylcyclopentane, is passed to reactor 18, in which it is intimately contacted with fluid aluminum chloride-hydrocarbon complex catalyst or other suitable catalyst, which is introduced through lines 5 and 19. After allowing the desired reaction time, the effluent from reactor 18 is passed through conduit 20 to settler 21 in which a heavier or catalyst phase separates from a lighter or hydrocarbon-rich phase. The heavier phase may be withdrawn through outlet 22 for revivification, but is preferably recycled at least in part through lines 23 and 19 to reactor 18. If necessary or desired, water or other materials for quenching the reaction may be introduced through line 31. The lighter hydrocarbon phase from settler 21 may be treated for removal of dissolved and/or suspended catalyst by means not shown. This phase is passed through line 24 to fractionator 25 which, in practice, is usually a series of fractionating columns. From fractionator 25, the following fractions are withdrawn: (1) A low-boiling fraction, comprising isobutane and t-butyl chloride, which is passed through lines 26 and 10 to fractionator 11 for resolution into its components. (2) A fraction comprising substantially pure methylcyclopentane, which is withdrawn through line 27 and passed thereby to reactor 35. (3) A fraction comprising unreacted 1-chloro-1-methylcyclopentane, which is recycled, as through lines 28 and 12, to reactor 18. (4) A kettle product, comprising relatively high-boiling hydrocarbons, which is withdrawn from the system through outlet 29.

The methylcyclopentane in line 27 is admixed with 2,2,4-trimethylpentane from line 33 and this mixture is contacted in reactor 35 with an aluminum halide isomerization catalyst from line 34, preferably aluminum bromide. A catalyst activator, such as the corresponding hydrogen halide, may also be used in reactor 35 if desired. From reactor 35 the reaction mixture passes through line 36 to separator 38, from which the catalyst is removed through line 39, for example as a water solution resulting from the addition of water as a quench from line 37. If practicable, a portion of the catalyst may be recycled to reactor 35 through lines 40 and 34. A hydrocarbon phase is passed from separator 38 through line 41 to fractionation means 42 which in practice is a series of fractionating columns. If further treatment of the hydrocarbon phase from separator 38 is required for removal of entrained or

dissolved catalyst, such treatment may be applied prior to entry of this phase into fractionation system 42. From fractionator 42 the following fractions are withdrawn: (1) A low-boiling fraction, comprising mainly isobutane, with or without usually smaller quantities of isopentane, both formed in reactor 35, which is withdrawn through line 43 and at least a part of which is passed through lines 32 and 12 to reactor 18 where it is used in a halogen-hydrogen exchange reaction with 1-chloro-1-methylcyclopentane. (2) A fraction comprising mainly unreacted methylcyclopentane but also containing a minor portion of cyclohexane, formed in reactor 35 by isomerization of methylcyclopentane therein, which is withdrawn through line 44 and is recycled in part through lines 45 and 27 to reactor 35, and a part of which is returned through lines 44 and 15 to reactor 4 for the eventual removal of the cyclohexane. (3) A fraction comprising mainly unreacted 2,2,4-trimethylpentane, which is withdrawn through line 46 and is recycled through lines 45 and 27 to reactor 35. (4) A fraction, comprising mainly octanes other than 2,2,4-trimethylpentane, which is withdrawn through line 47 as a product of the process. (5) A fraction comprising higher-boiling hydrocarbons which is withdrawn through line 48.

The preferred temperature range for the first halogen-hydrogen exchange reaction, carried out in reactor 4, is 0 to 40° C., although much lower temperatures may also be used. Elevated pressures sufficient to maintain the reaction mixture in liquid phase are preferred. The reaction time should be short and is usually within the range of 0.05 to 10 minutes; a reaction time of one minute is ordinarily preferred, inasmuch as long reaction times favor undesired side reactions with consequent reduction in ultimate yield. Although the proportion of the tertiary or secondary alkyl halide added is not critical, it is preferred that the mol ratio of added alkyl halide to methylcyclopentane be at least about 1:1, and preferably somewhat in excess thereof. Aluminum bromide as well as aluminum chloride is a highly satisfactory catalyst. Other active metal halides of the Friedel-Crafts type may likewise be used. The catalyst may be employed in any conventional form, but preferably a hydrocarbon-aluminum halide complex is employed which takes the form of a heavy liquid containing from 40 to 60 or 70 weight per cent aluminum halide. Although the halogen of the catalyst need not necessarily correspond to the halogen of the added tertiary or secondary alkyl halide, it is preferred that they so correspond in order to facilitate recovery or reuse of materials without having to contend with exchange of halogen between catalyst and reactants. Relatively small amounts of catalyst are required, preferably ranging from 1 to 5 weight per cent of the reaction mixture, although smaller amounts such as 0.5 per cent or lower, or larger amounts up to 10 or even 25 per cent, or more, are operable.

Reaction conditions of temperature, pressure, time, and catalyst for the second halogen-hydrogen exchange reaction, carried out in reactor 18, may be similar to those described above for reactor 4 although it is preferred that the mol ratio of added tertiary hydrocarbon (isobutane and/or isopentane) to the tertiary halide 1-chloro-1-methylcyclopentane which is to be reconverted into the original methylcyclopentane be at least

about 1:1, and preferably somewhat in excess thereof.

Although tertiary butyl chloride is the preferred reactant for the first halogen-hydrogen exchange reaction, various other tertiary, or less preferably secondary, alkyl and cycloalkyl halides, preferably the chlorides and bromides, may be employed so long as the boiling point relationships described hereinabove are such as to allow recovery of the desired intermediate 1-chloro-1-methylcyclopentane by simple fractional distillation. Thus, isopropyl chloride, sec-butyl bromide, 2-chloro-2-methylbutane (tert-amyl chloride), and other halides containing not in excess of seven carbon atoms per molecule, may be used.

The following data are given to illustrate specific conditions suitable for practicing the halogen-hydrogen exchange reaction steps of the invention. It will be appreciated, of course, that the exact conditions stated are merely exemplary and are not limiting as to the broader aspects of the invention.

A mixture of 114.7 grams of t-butyl chloride (1.24 moles), 114.3 grams of methylcyclopentane (1.36 moles) and 38.5 grams of cyclohexane, cooled in ice, was stirred vigorously with 4.0 grams of AlCl_3 for 120 seconds. Then 25 cc. of water was added to wash out the AlCl_3 . When the dried hydrocarbon mixture was fractionated, there were obtained 18.1 grams (0.31 mole) of isobutane, 76.2 grams (0.83 mole) of unreacted t-butyl chloride, 84.9 grams (1.01 moles) of unreacted methylcyclopentane, 32.2 grams of cyclohexane, 36.0 grams (0.30 mole) of 1-chloro-1-methylcyclopentane and 4.1 grams of high-boiling residue.

A mixture of 150.2 grams (1.27 moles) of 1-chloro-1-methylcyclopentane prepared in several runs from a mixture of methylcyclopentane and cyclohexane as described above, and 107 grams

10

15

20

(1.2 moles), 36.5 grams of t-butyl chloride (0.40 mole), 41 grams of the regenerated methylcyclopentane (0.49 mole), 80 grams (0.68 mole) of unreacted 1-chloro-1-methylcyclopentane, and some high-boiling residue.

Suitable conditions for the isomerization of 2,2,4-trimethylpentane, in addition to requiring the presence of methylcyclopentane as inhibitor, involve the use of moderate temperatures and reaction times. The reaction is best conducted in the liquid phase. Temperatures of from -30 to $+50^\circ\text{C}$. are suitable, with the range of -10 to $+30^\circ\text{C}$. being preferred. Other factors being equal, decreased temperatures give increased ultimate yields, though the reaction rate is slowed. Contact times of from 1 to 500 minutes are generally satisfactory, with two hours or less, or preferably one hour or less, usually employed. The quantity of catalyst may be varied considerably without greatly affecting the ultimate yield of octanes, at least within the range of 2 to 15 weight per cent aluminum chloride based on the weight of 2,2,4-trimethylpentane charged. Even small quantities of methylcyclopentane are helpful; I prefer to employ a mixture of 2,2,4-trimethylpentane and methylcyclopentane containing at least 10 weight per cent of the latter, and up to 25 or even 50 per cent may be used. Suitable catalyst activators and various other isomerization procedures known to the art may be used as desired.

The data presented in Table I are examples of results obtainable in the isomerization of 2,2,4-trimethylpentane with aluminum bromide catalyst. The runs were carried out at 26°C . in a 500 ml. glass flask; at the end of the specified reaction time the aluminum bromide was washed out with water. Obviously these runs are only exemplary, and not necessarily representative of the optimum conditions for all cases.

(1.84 moles) of isobutane, was stirred with about 6 grams of AlCl_3 at 0°C . for about 7 minutes. Water was added, the material then dried, and the dried reaction mixture was fractionated. There were obtained about 70 grams of isobutane

75 yield of octanes from the 2,2,4-trimethylpentane. Run 1 is an average of the data of 10 runs on the isomerization of 2,2,4-trimethylpentane alone. Runs 3, 4, 5 and 7 illustrate the beneficial effect of methylcyclopentane on the ultimate

A comparison of run 3 with run 4 and of run 5 with run 7 shows that, in the presence of methylcyclopentane, better ultimate yields of octanes are obtainable at the lower conversions. A considerable portion of the methylcyclopentane is consumed, possibly by alkylation or other reactions. It is preferable to recycle methylcyclopentane recovered from effluents in order to maintain a high concentration of methylcyclopentane in the reaction mixture. But run 5 shows that some cyclohexane is formed by isomerization of methylcyclopentane during the isomerization of the 2,2,4-trimethylpentane; and therefore provision must be made for the continuous removal of the cyclohexane which would otherwise build up in the reaction mixture. Such provision is described hereinabove. Runs 2 and 6 show that cyclohexane has no beneficial effect on the ultimate yield of octanes from the 2,2,4-trimethylpentane; and the total weight per cent of C₆ plus C₇ in each of these runs indicate that the cyclohexane is unchanged. A much larger quantity of the AlBr₃ goes to sludge with cyclohexane added than with methylcyclopentane added. It appears that, in order to inhibit side reactions during 2,2,4-trimethylpentane isomerization, a naphthene must have a reactive tertiary hydrogen, as in methylcyclopentane. Since normal hexane, like cyclohexane, has no reactive tertiary hydrogen, it would be expected to be inert during 2,2,4-trimethylpentane isomerization with aluminum bromide at the low temperatures specified here. It lacks the beneficial inhibiting effects of methylcyclopentane and is an undesired diluent since it is not isomerized itself under these conditions.

I claim:

1. A process which comprises subjecting a hydrocarbon mixture partially derived from an extraneous source and partially derived from a recycle stream hereinafter described, said mixture comprising methylcyclopentane and cyclohexane, to reaction with a halide selected from the group consisting of secondary and tertiary alkyl and cycloalkyl halides under conditions effecting halogen-hydrogen exchange reaction to form 1-halo-1-methylcyclopentane, separating from the reaction mixture by fractional distillation 1-halo-1-methylcyclopentane so produced, reacting same with a low-boiling saturated hydrocarbon having a tertiary carbon atom and at least partially derived as hereinbefore described under conditions effecting halogen-hydrogen exchange reaction re-forming methylcyclopentane, subjecting 2,2,4-trimethylpentane in admixture with thus-formed methylcyclopentane to isomerization in the presence of an aluminum halide isomerization catalyst selected from the group consisting of aluminum chloride and aluminum bromide under conditions forming isomeric octanes and low-boiling saturated paraffin hydrocarbon having a tertiary carbon atom, said methylcyclopentane inhibiting side reactions during said isomerization, recovering isomeric octanes so produced as a product of the process, passing at least a portion of said low-boiling saturated paraffin hydrocarbon having a tertiary carbon atom to halogen-hydrogen exchange reaction with said 1-halo-1-methylcyclopentane as hereinbefore described, recovering from effluents of said isomerization a fraction comprising unreacted methylcyclopentane containing in admixture therewith cyclohexane formed by isomerization of methylcyclopentane, recycling a portion of said fraction to said isomerization,

and passing a portion of said fraction as part of said hydrocarbon mixture to halogen-hydrogen exchange reaction with said halide to separate from cyclohexane the methylcyclopentane content thereof as hereinbefore described.

2. A process which comprises subjecting a hydrocarbon mixture partially derived from an extraneous source and partially derived from a recycle stream hereinafter described, said mixture comprising methylcyclopentane and cyclohexane, to reaction with a halide selected from the group consisting of secondary and tertiary alkyl and cycloalkyl halides in the presence of a Friedel-Crafts type metal halide catalyst under conditions effecting halogen-hydrogen exchange reaction to form 1-halo-1-methylcyclopentane, said conditions comprising temperatures not exceeding 40° C. and reaction time not exceeding 10 minutes, separating from the reaction mixture by fractional distillation 1-halo-1-methylcyclopentane so produced, reacting same with a low-boiling saturated hydrocarbon having a tertiary carbon atom and at least partially derived as hereinbefore described in the presence of a Friedel-Crafts type metal halide catalyst under conditions effecting halogen-hydrogen exchange reaction re-forming methylcyclopentane, said conditions comprising temperatures not exceeding 40° C. and reaction time not exceeding 10 minutes, subjecting 2,2,4-trimethylpentane in admixture with thus formed methylcyclopentane to isomerization in the presence of an aluminum halide isomerization catalyst selected from the group consisting of aluminum chloride and aluminum bromide under conditions comprising temperatures within the range of -30 to +50° C. and reaction time not exceeding two hours forming isomeric octanes and low-boiling saturated paraffin hydrocarbon having a tertiary carbon atom, said methylcyclopentane inhibiting side reactions during said isomerization recovering isomeric octanes so produced as a product of the process, passing at least a portion of said low-boiling saturated paraffin hydrocarbon having a tertiary carbon atom to halogen-hydrogen exchange reaction with said 1-halo-1-methylcyclopentane as hereinbefore described, recovering from effluents of said isomerization a fraction comprising unreacted methylcyclopentane containing in admixture therewith cyclohexane formed by isomerization of methylcyclopentane, recycling a portion of said fraction to said isomerization, and passing a portion of said fraction as part of said hydrocarbon mixture to halogen-hydrogen exchange reaction with said halide to separate from cyclohexane the methylcyclopentane content thereof as hereinbefore described.

3. A process which comprises subjecting a hydrocarbon mixture partially derived from an extraneous source and partially derived from a recycle stream hereinafter described, said mixture comprising methylcyclopentane, cyclohexane and normal hexane, to reaction with a tertiary alkyl halide under conditions effecting halogen-hydrogen exchange reaction to convert said methylcyclopentane to 1-halo-1-methylcyclopentane while leaving said normal hexane and cyclohexane unreacted, separating from the reaction mixture by fractional distillation 1-halo-1-methylcyclopentane so produced, reacting same with isobutane which has been at least partially derived as hereinbefore described under conditions effecting halogen-hydrogen exchange reaction re-forming methylcyclopentane, sub-

11

jecting 2,2,4-trimethylpentane in admixture with thus-formed methylcyclopentane to isomerization in the presence of an aluminum bromide isomerization catalyst under conditions forming isomeric octanes and isobutane, said methylcyclopentane inhibiting side reactions during said isomerization, recovering isomeric octanes so produced as a product of the process, passing at least a portion of said isobutane to halogen-hydrogen exchange reaction with said 1-halo-1-methylcyclopentane as hereinbefore described, recovering from effluents of said isomerization a fraction comprising unreacted methylcyclopentane containing in admixture therewith cyclohexane formed by isomerization of methylcyclopentane, 10 recycling a portion of said fraction to said isomerization, and passing a portion of said fraction as part of said hydrocarbon mixture to

5

12

halogen-hydrogen exchange reaction with said tertiary alkyl halide to separate from cyclohexane the methylcyclopentane content thereof as hereinbefore described.

FRANCIS E. CONDON.
